UNITED STATES PATENT OFFICE.

GEORGE F. WILSON, OF PROVIDENCE, RHODE ISLAND.

IMPROVEMENT IN PUTTING UP BAKING-POWDERS.

Specification forming part of Letters Patent No. 118,768, dated September 5, 1871.

To all whom it may concern:

Be it known that I, GEORGE F. WILSON, of Providence, in the county of Providence and State of Rhode Island, have invented a new and useful Mode of Putting up Baking-Powders and other articles of a like character, of which the following is a specification:

If the several ingredients which enter into the composition of what are known as baking-powders be kept separate until the time when they are required to be mixed for actual use, the powders will preserve their quality and efficiency a much longer time than if they were packed and mixed together in the same can. My invention is intended to keep the several ingredients of these powders separate, and it is applicable not only to baking-powders, so called, but to other articles or compounds, the ingredients of which should be kept separate until required for use. The invention consists in the putting up, in one can or case of the powder or other article in such manner that each ingredient of the same shall occupy a compartment or space in the can separate and isolated from the other. It further consists in the use for this purpose of a sheet-metal can divided into two parts—each closed at the bottom to form a chamber for the reception of one of the ingredients of the powder, the upper part being provided with a removable cover, and fitting and forming the cover of the lower part.

The manner in which my invention is or may be carried into effect will be readily understood by reference to the accompanying drawing, in which—

Figure 1 represents, in perspective, the several parts of a can which I prefer to use in carrying my invention into effect. Fig. 2 is a vertical central section of the can, with all the parts shown separately in Fig. 1 fitted together.

The can is divided into two parts, Δ B, each provided with a bottom, a b, for the purpose above stated, the one part having the same exterior form as the other, so that when the two are put together they may appear to be one and the same can.

The capacity of the chambers is regulated by the quantity of the powder or other ingredient they are to contain.

In the present case the upper part A is intended to contain the cream-tartar or acid, and the lower part B the soda, used in making baking-powders, and the parts are, therefore, of such size as to hold the proper proportion of each re-

quired to form the powders. The upper part A fits in or upon or over the top of the lower part B and forms the cover of the same, as seen in Fig. 2, and it is provided itself with a cover, C, which fits it, as shown in the figure referred to. The different ingredients of the powder can be thus kept separate and isolated from each other, and yet they are put up in a can not differing in extreme appearance from an ordinary can, and they may be put in the market and sold like ordinary baking-powders. Of course, if there are more than two ingredients which enter into the composition of the powder or other preparation intended to be thus put up the can must have a corresponding number of compartments—that is to say, it may have one bottom part, B, and two or more upper parts, A, the upper one fitting and forming the cover of the next lower ones and the top one closed by a cover, C.

In lieu of a can made as shown in the drawing, the body B of the can might be opened at both ends with a horizontal partition dividing it into two parts, each proportionate in size to the quantity of powder to be put in it, and then the two ends might each be closed by covers, so that by turning one of the other of the ends up and removing its cover access might be had to either of the ingredients without disturbing the other. And it is manifest that the can may be made in other ways, so that the ingredients shall be held each separate and isolated from the others, and so that the chamber containing one may be opened without disturbing the other.

Having now described my invention and the manner in which the same is or may be carried into effect, what I claim, and desire to secure by Letters Patent, is as follows:

1. The mode of putting up baking-powders and other similar preparations, substantially as herein described.
2. A sheet-metal can for putting up baking-powders and other preparations, composed of two or more parts, each closed at the bottom, the upper one fitting and forming the cover of the one next below, and the top one being provided with a cover, substantially as herein shown and described.

In testimony whereof I have signed my name to this specification before two subscribing witnesses.

GEO. F. WILSON.
